UNITED STATES PATENT OFFICE.

JOHN SEVERDING, OF RICHMOND, INDIANA.

RAIN-WATER CUT-OFF.

SPECIFICATION forming part of Letters Patent No. 351,940, dated November 2, 1886.

Application filed March 29, 1886. Serial No. 196,858. (No model.)

To all whom it may concern:

Be it known that I, JOHN SEVERDING, a citizen of the United States, residing at Richmond, in the county of Wayne, State of Indiana, have invented certain new and useful Improvements in Rain-Water Cut-Offs, of which the following is a specification, reference being had therein to the accompanying drawings.

10 My invention relates to that class of rain-water cut-offs intended to change the discharge at pleasure.

My invention consists of the devices herein-after described and claimed.

15 In the drawings, Figure 1 is a side elevation. Fig. 2 is a longitudinal vertical section showing the cut-off valve. Fig. 3 is a vertical cross-section. Fig. 4 is a perspective of the bracket forming the ear of the hinge. 20 Fig. 5 is a perspective of the curved shaft by which the cut-off valve is operated. Fig. 6 is an outline plan of the sheet forming one half of the body of the cut-off. Fig. 7 is an outline plan of the sheet forming the cut-off 25 valve.

In Fig. 1, A represents a tubular body formed of two pieces of sheet metal joined together in the center, having an inlet-opening, B, and independent outlet-openings C C, 30 of equal sizes.

B' is the hand-lever, forming part of a curved shaft, B'', hinged to the sides of the body A, centrally at n, and which is allowed a swinging motion to the extent of 35 a half-circle, as shown in dotted lines in Fig. 1. The curved shaft B'' extends in a semicircular form across the space inside the body A, as seen at Fig. 3, the pivots upon which it turns being in a horizontal plane 40 and secured to the sides of the body, having holes e e, through which the pivots forming the axis are inserted. The axis is composed of an ear, D, Fig. 4, having projecting flanges d d, leaving a depression between them, into 45 which the bar of the curved arm or shaft B'' is fitted, the pivot n' passing through the hole e of the shaft and the hole n of the ear D, and through the side of the body A and through the cut-off-valve a, where the pivot 50 n' terminates in a head or flange, which holds

the cut-off valve a in position, and at the same time allows it to tilt independently within the limits of the curved shaft B'', there being a space, a', between them, as seen in Figs. 2 and 3. The ear D, which embraces 55 the bar of the curved shaft B'', turns with the shaft, and the projections d d have their bearings upon an annular boss, h, which projects outward slightly from the surface of the body A.

The cut-off valve is formed of an oval sheet of metal, as in Fig. 7, having the sides bent up in circular form in cross-section, and of proper size to conform to the radius of the inside of the inlet and outlet openings of the 65 body A. It is adapted to be turned either way from the inlet-opening, so as to form, in conjunction with the inlet-opening, a continuous tube with either of the outlet-openings, as seen in dotted lines in Fig. 2. The cut-off 70 valve is turned or tilted in either direction to accomplish this result by the action of the curved shaft B'', operated by the hand-lever portion of the same as it comes in contact with the under side of the valve, on either 75 side of the center thereof, and raising that end of the valve into the position desired.

When the hand-lever B' is in a vertical position and the cut-off valve is in a horizontal position, as seen in Fig. 2 of the drawings, a 80 space, a', exists between the curved shaft B'' and the bottom surface of cut-off a, which allows either one of them to be moved or tilted without moving the other. By this arrangement it will be seen that a much greater 85 force is exerted upon the cut-off valve a when applied by means of the curved shaft on one side of the center than is possible when the cut-off is secured to a wire or other axis at a fixed point, and obviates any danger of tearing the axis loose from the valve when frozen or otherwise obstructed.

I am aware that a rain-water cut-off has been made having a body made up of a main supply-pipe and elbows connected thereto, in 95 which a cut-off valve is operated by and secured to a wire pivoted to the pipes. This I do not claim; but

What I do claim as my invention, and desire to secure by Letters Patent, is—

A rain-water cut-off composed of the body A, constructed as described, the cut-off valve a, curved shaft B", having handle-lever B', axis-pin n', ear D, and boss h, all combined and operating substantially in the manner and for the purpose herein set forth and described.

In testimony whereof I affix my signature in the presence of two witnesses.

JOHN SEVERDING.
